(57) **CLAIM**

The ornamental design for a personal grooming tool, as shown and described.

DESCRIPTION

FIG. 1 is a top plan view of a personal grooming tool showing our new design;

FIG. 2 is a bottom plan view thereof.

FIG. 3 is a left side elevational view thereof; the right side elevational view is a mirror image of the left side elevational view.

FIG. 4 is a perspective view thereof.

FIG. 5 is an isometric view thereof.

FIG. 6 is a perspective view thereof.

FIG. 7 is a view of the left end thereof; and,

FIG. 8 is a view of the right end thereof.

1 Claim, 3 Drawing Sheets
